Primary Examiner — Anhdao Doan(74) *Attorney, Agent, or Firm* — Popovich, Wiles & O'Connell, P.A.(57) **CLAIM**

The ornamental design for a landscaping block, as shown and described.

DESCRIPTION

FIG. 1 is a front top perspective view of an embodiment of a landscaping block according to my new design;

FIG. 2 is a front view thereof;

FIG. 3 is a top plan view thereof;

FIG. 4 is a bottom plan view thereof;

FIG. 5 is a rear elevational view thereof;

FIG. 6 is a left side elevational view thereof; and

FIG. 7 is a right side elevational view thereof.

FIG. 8 is a front top perspective view of an embodiment of a landscaping block according to my new design;

FIG. 9 is a front bottom perspective view thereof;

FIG. 10 is a front view thereof;

FIG. 11 is a top plan view thereof;

FIG. 12 is a bottom plan view thereof;

FIG. 13 is a rear elevational view thereof;

FIG. 14 is a left side elevational view thereof; and,

FIG. 15 is a right side elevational view thereof.

The broken line showings of FIGS. 1 to 15 are for illustrative purposes and form no part of the claimed design.
